LOUD SPEAKER

Filed Aug. 16, 1926

Nathaniel Baldwin INVENTOR

UNITED STATES PATENT OFFICE.

NATHANIEL BALDWIN, OF EAST MILL CREEK, UTAH.

LOUD-SPEAKER.

Application filed August 16, 1926. Serial No. 129,459.

The present invention appertains to loud speakers and particularly to those in which large diaphragms or sound boards are used to produce the sound.

5 The principal object is to provide a simple and efficient fulcrum for the armature used in such loud speakers and particularly to provide a fulcrum which is suitable for such armature when disposed at an angle with the 10 link connecting such armature to the diaphragm or other sound producing element.

I attain this and other objects by the mechanism illustrated in the accompanying drawing in which Fig. 1 is a section of the instrument as applied to a sound board such as a 15 panel of a door, and Fig. 2 is an elevation of part of the structure shown in Fig. 1.

Numeral 1 designates the armature to be used and numeral 2 designates a spool having a central tubular portion and containing the actuating coil. The armature passes centrally through the tubular portion of the spool and is connected internally with said spool by means of a flexible fulcrum 3 consisting of a piece of sheet metal ribbon bent at angles so as to provide a straight part connecting the armature with the spool center and flat surfaces at either end to fasten to the armature and spool center. The middle part 25 of this fulcrum ribbon may be made more flexible by perforating it and cutting away portions as indicated in Fig. 2.

The spool is held in position by U-shaped polepieces 4 and 5 which are secured to the poles of the horseshoe magnet 6. In the structure as here illustrated the magnet 6 is secured to a bar 7 by means of a screw 8 and cross bar 9, and the bar 7 is secured to a door by means of the screws 10, 11 and 12. The 35 screw 11 passing through the bar 7 is tapped into the door 13 and carries a coil spring 14 which tends to press the bar 7 against the door 13. The position of the bar 7 is adjustable by means of the screw 12.

45 A link 15 attached to the armature and having an enlarged portion at one end presses upon the panel 16 and communicates the vibration of the armature to the panel. A pressure upon the link 15 is maintained by a 50 spring 17 seated in the polepiece 4 and pressing against the armature. It will be seen that the position of the armature between the polepieces is adjustable by means of the screw 12.

I claim:

1. A loud speaker comprising a spool, an actuating coil on said spool, an electrically operated armature fulcrumed within the spool, and a fulcrum of sheet metal, upon which said armature is permanently mounted. 55

2. A loud speaker comprising a spool, an actuating coil on said spool, an operating armature within said spool, and a fulcrum of sheet metal nondetachably connected to said armature and to said spool. 60

3. A loud speaker comprising a spool, an actuating coil on said spool, an operating armature within said spool, and a fulcrum of sheet metal fixed to said armature and to said spool. 65

4. A loud speaker comprising a spool, an actuating coil on said spool, an operating armature within said spool, a fulcrum of sheet metal for said armature and within said spool, a sound producing element, and a link in operative relation with said armature and 70 said sound producing element, said link being disposed at an obtuse angle with said armature. 75

5. A loud speaker comprising a spool, an actuating coil on said spool, an operating armature within said spool, a fulcrum of sheet metal for said armature and within said spool, a soundboard, and a link in operative relation with said armature and said soundboard, said link being disposed at an obtuse angle with 80 said armature. 85

6. A loud speaker, comprising an actuating coil, a sheet metal fulcrum within said coil, and an armature mounted on said fulcrum, the said fulcrum being disposed obliquely to said armature. 90

7. A loud speaker, comprising an actuating coil, a fulcrum within said coil, and an armature mounted on said fulcrum, a portion of said fulcrum being non-parallel to said armature and being so arranged with respect to said armature that functioning of said fulcrum imparts a longitudinal motion to said armature. 95

8. A loud speaker, comprising an actuating coil, a fulcrum within said coil, and an armature mounted upon said fulcrum, the said fulcrum being formed of a strip of sheet metal having a flexing portion disposed obliquely to said armature. 100

NATHANIEL BALDWIN.
